DESIGN.

—o—

A. B. CAMERON.
PANEL.

No. 20,380.

Patented Dec. 9, 1890.

UNITED STATES PATENT OFFICE.

ALLAN B. CAMERON, OF WILLIAMSPORT, PENNSYLVANIA.

DESIGN FOR A PANEL.

SPECIFICATION forming part of Design No. 20,380, dated December 9, 1890.

Application filed November 12, 1889. Serial No. 330,078. Term of patent 14 years.

To all whom it may concern:

Be it known that I, ALLAN B. CAMERON, of Williamsport, Lycoming county, Pennsylvania, have invented and produced a new and original Design for Panels, of which the following is a specification, reference being had to the accompanying photograph, forming part hereof.

The figure represents my design.

My design relates to an ornamental panel. On the surface of said panel appears a rectangular elevation A. From the center B of said elevation channels, as C, extend to the edges of said elevation A. I may vary the

number of channels at will. The edges of the elevation A and of the channels C are rounded. The triangular elevations which appear between the channels C have their apexes meeting at the central point of the panel.

I claim—

The design for an ornamental panel, substantially as herein shown and described.

ALLAN B. CAMERON.
